(57) **CLAIM**

The ornamental design for a foldable magnifier with lighting arrangement, as shown and described.

DESCRIPTION

FIG. 1 is a perspective view of a foldable magnifier with lighting arrangement showing my new design;

FIG. 2 is a front view thereof;

FIG. 3 is a rear view thereof;

FIG. 4 is a right end view thereof;

FIG. 5 is a left end view thereof;

FIG. 6 is a top view thereof;

FIG. 7 is a bottom view thereof;

FIG. 8 is a perspective view thereof, shown in an alternative in-use position; and,

FIG. 9 is a perspective view thereof, shown in a folded position.

The broken lines depict portions of the foldable magnifier with lighting arrangement that form no part of the claimed design.
